United States Patent Office.

JAMES L. JACKSON, OF NEW YORK, N. Y.

Design No. 4,377, dated October 4, 1870.

DESIGN FOR IRON RAILING FOR HORSE-STALLS.

The Schedule referred to in these Letters Patent and making part of the same

To all whom it may concern:

Be it known that I, JAMES L. JACKSON, of the city and State of New York, have invented or produced a new and original Design for an Iron Railing; and the following is declared to be a correct description thereof.

This railing is especially adapted to the upper part of the divisions between horse-stalls, and is usually designated a "ramp."

The outline of the railing is straight at the bottom, and a compound curve, *a*, on the upper portion uniting the lower portion *b* of the top rail to the higher portion *c*, as shown in the accompanying photographic view.

The railing is made with vertical bars *b*, and with intersecting bars *e f*, parallel to the top rail *a b c* and

bottom rail *g*, and there are ornaments around the bars *d*, near the intersections.

A post, *h*, at the end of the ramp completes the ornamental configuration shown, but said post *h* might be dispensed with.

An ornament, as shown at *i*, may be used to connect the middle portions of the bars *d*.

I claim as my invention—

The design of the ornamental shape and configuration of the railing, substantially as described and represented.

Signed this 8th day of August, A. D. 1870.

JAMES L. JACKSON.
